ELECTROTHERAPEUTIC APPARATUS

Eugen Weissenberg, Vienna, Austria

Application April 4, 1934, Serial No. 719,009
In Austria July 15, 1932

5 Claims. (Cl. 128—1.3)

This invention relates to new and improved electro-therapeutic apparatus, operating with high frequency alternating fields, for example with short waves. It is a known fact that with 5 a large variety of lesions and disorders valuable therapeutic effects can be obtained by treatment in a high frequency alternating field, for example by treatment with short waves, provided sufficiently large quantities of energy are brought 10 to bear. The aim in this connection has hitherto been primarily to turn to account therapeutically the heat of resistance (joule heat) set up in the body by the current, and since the thermal equivalent is very high it has been found necessary to 15 work with relatively high generator output (about 1.5 kw.). It has been a further aim hitherto to increase as far as possible the amount of energy administered to the patient, which has led to the 20 constant development of apparatus of greater and greater emitting power, and to the principle of carrying out the treatment in the region of maximum energy, that is to say in the condenser field or in the coil field.

The types of treatment of this description 25 which have as yet become known are attended by a number of serious drawbacks. In the first place, the apparatus used is very cumbrous and costly, so that the practitioner has heavy initial expenses to bear, the operation of the apparatus 30 is expensive, in consequence of the high current consumption, and dangerous in view of the high tension current used. To these drawbacks there must be added the further disadvantage that, in consequence of the lack of a reliable method of 35 measuring the amount of energy administered, the danger of injury to the patient through overdosing cannot be obviated with certainty. The use of therapeutic appliances of the known kind is practically contingent upon the reservation for 40 this purpose of a special room, and in view of the danger involved, upon the employment of specially trained assistants for the administering of the treatment. The amortization of the heavy initial costs and running expenses is difficult 45 of achievement, since it is not possible to irradiate more than one person at a time in the condenser or coil field. Finally, a still further drawback of the known types of apparatus consists in the fact that a large proportion of the 50 energy emitted goes to waste, and that this uselessly dispersed energy causes annoyance by interfering with wireless reception. The elimination of this latter objection is only possible at great expense, and with serious detriment to the 55 effectiveness of the apparatus.

The present invention has taken an entirely new course for the purpose in view, and has succeeded not only in overcoming these drawbacks of existing methods of treatment, but in addition in widening the scope of the treatment 5 concerned, and in providing new spheres of application for treatment of this kind. The course adopted is founded on the knowledge, acquired as the result of many years of clinical experiment, that nerves (and more particularly diseased and disordered nerves) react to the influence of a very small fraction, say 1/1000, of the amount of electro-magnetic energy usually 10 administered, and that this reaction is in many respects specifically different from that brought 15 about by irradiation with the usual large amounts of energy, provided that the particular measures constituting this invention be observed. The chief of these measures are, in the first place 20 the carrying out of the irradiation in the field of the free advancing electro-magnetic waves (instead of the condenser or coil field), and in the second place arranging for adequate inhomogeneity of the strength of the field in the region 25 occupied by the irradiated body. The specific affects obtainable will first be discussed in the light of a few examples, after which the new inventive steps, based on the above-mentioned discovery, will be defined and characterized.

With certain nervous disorders, more particularly with disturbances of the vegetative and sensory nervous system, the irradiation, as commonly practised, has no ameliorative effect, but on the contrary often causes violent attacks of pain and convulsion, which even occur partly 30 during the irradiation. If the amount of energy applied be reduced the unfavorable reaction becomes as a rule less pronounced. Over and above this observed effect, a novel result, specific 35 to and characteristic of the method according to the present invention, namely rapid alleviation of pain and spasms and continued improvement of the symptoms of disorder, is obtained if the irradiation be carried out, in accordance with the present invention, with very slight amounts of 40 energy and, in a manner to be described in due course, in the field of the free advancing waves and in an adequately inhomogeneous field. The new effect is also distinguishable from the sedative 45 action exerted by the application of heat 50 however effected (hot compresses, diathermic treatment, and the like) in that this effect is achieved by means of the slight amounts of energy applied in accordance with the invention, without the production of any heat at all. This 55

specific effect of the new method of treatment, when used on diseased or disordered nerves, is possibly due to the fact that nerve fibres react in general to relatively very slight electric stimuli, and that the small amounts of energy employed in accordance with the invention are approximately of the same order of magnitude as the currents due to action in the tissues of the body, the inhomogeneity of the field strength being 10 favorable to the occurrence of the therapeutically effective electric stimuli.

The applicability of the new method of treatment is by no means confined to the cases indicated above, which are only mentioned by way 15 of example. The nerves admittedly control the entire biological processes in the organism, and by influencing the nerve tissue a therapeutic effect can therefore be exercised indirectly upon a great variety of lesions and disorders.

20 The discoveries of a medical nature outlined above open the way for the devising of new technical measures and means with the aid of which the above-described favorable therapeutic effects can be achieved.

25 The present invention is distinguishable from the known methods and from the apparatus required for the carrying out of these methods more particularly by the fact that the apparatus according to the present invention provides for 30 the generation of an electro-magnetic alternating field having an adequately low energy density coupled with an adequately high degree of inhomogeneity. The adequately low energy density is provided for either by making the apparatus 35 in the form of a small scale wave-sender constructed as a safety set which, either with self-excitation or with extraneous control, emits the electro-magnetic waves, or by utilizing the free advancing electro-magnetic waves hitherto emitted 40 to no purpose by the large capacity senders used for therapeutic purposes. The required high degree of inhomogeneity in the strength of the field is achieved, with the aid of the means provided in accordance with the invention, either 45 by producing inhomogeneity by additional measures, in an existing substantially homogeneous electro-magnetic field, or intensifying existing inhomogeneity, or by generating an initially highly inhomogeneous field by means of suitable apparatus.

50 In the present connection, the term "inhomogeneity" is to be taken as meaning diversity of field strength within the space occupied by the object of treatment, the arrangement according 55 to the invention being designed to render it possible for the diversity of field strength within the space concerned to be increased to a maximum. By virtue of this maximum diversity of field strength, that is to say, for example, of very sudden drops in the strength of the field 60 from one region to another of the field, there occur in the subject of the treatment differences of potential which give rise to therapeutic action.

The present invention also deviates fundamentally from the methods hitherto adopted, which are based on the principle of irradiating in the electric condenser or coil field, by effecting the treatment mainly in the free space occupied by electro-magnetic oscillations, and more particularly in the field of the free advancing electro-magnetic waves. In accordance with the invention the new method of treatment can be carried out with the aid of apparatus characterized substantially by the following features.

75 (a) The employment of a readily portable

small scale wave-sender in the form of a safety set which can be plugged into any ordinary main of a voltage up to about 500 volts. The set is preferably totally enclosed in a casing of insulating material, the energy being emitted by radiating elements situated within the casing.

In this case the required inhomogeneity is ensured by the arrangement that the space occupied by the field produced by the small capacity sender is slight in comparison with that occupied by the object of treatment. The great differences in field strength present in this field thus become fully effective within the range of the space occupied by the object of treatment.

The adequately low energy density of the field, 15 and with it the safety (absence of danger), is ensured by so dimensioning the individual parts of the small capacity sender that the energy emitted cannot exceed a predetermined limit which is set so low that the possibility of inflicting 20 injury to patients through overdosing, is precluded. In this way also the disturbing of wireless reception in the neighbourhood of the apparatus is likewise effectually prevented.

(b) The use of a high frequency alternating 25 field derived from an extraneously controlled sender operated by voltages transmitted from a broadcasting transmitting station, if necessary with suitable amplification.

In this case the inhomogeneity of the field is 30 brought about in the same manner as in (a), the safety of the apparatus being likewise ensured for the same reasons as those given above.

(c) The provision for each patient, in a space 35 traversed by electro-magnetic radiation, of one or more conductors belonging neither to the generator circuit nor to a treatment circuit closely coupled therewith, the number, size, arrangement, and shape of these conductors being such that they vary the field locally in the required 40 manner, without the variation of their number, size, shape, and arrangement exerting any appreciable reactive effect upon the total output consumption of the set, so that these conductors are capable of supplying the energy, dosed both as 45 to quantity and as to quality, to one or more patients simultaneously.

In the latter case there is effected by the conductors a concentration or an inhomogeneous distortion of the initially homogeneous or approximately homogeneous field, and the field strength distribution is so influenced that field strengths varying very greatly in magnitude are brought to bear upon the object of treatment.

A particular advantage of the last-described 55 arrangement is the possibility which it affords of treating a large number of patients simultaneously, and at the same time of varying the doses of energy administered to the patients individually. As a further result of the independence of the conductors from the sender it becomes possible to carry out treatment from a 60 distance, and to administer treatment for example, to patients who are confined to bed or who are incapable of being transported, from a 65 remote central apparatus. The distances at which treatment can thus be carried out with a therapeutic field obtainable with the usual sender outputs, are very considerable.

The employment of the advancing electro-magnetic waves in accordance with the invention also provides the possibility of utilizing optical means to obtain certain directional and remote effects, by interference, reflection, polarization, beaming, and the like.

In accordance with the invention the optical means employed are either provided in the form of an auxiliary attachment associated with the sender, or are arranged independently of the 5 sender in the vicinity of the patient.

Particular advantages also result from the fact that the apparatus according to the invention can be readily combined with other therapeutic radiating apparatus, such as light or heat radiators, for the obtaining of combined effects.

Finally, it is worthy of mention that the new 10 method of treatment permits of the utilization for therapeutic purposes of ranges of frequency which have not hitherto been utilizable for such 15 purposes, or only with great difficulty and with the use of very high outputs, namely the ultra-short wave ranges. But it is precisely these 20 ranges of frequency which are particularly readily influenced by interference, and which afford very definite advantages when turned to account therapeutically.

Attempts have hitherto been made to obviate the danger of injury to the patient by overdosing, when the usual types of apparatus are used 25 and the treatment carried out in the condenser or coil field, by reducing the amount of energy expended in the treatment to such an extent that no appreciable heat development takes place. However, the conditions provided by the 30 present invention, namely a field of sufficiently low energy density and at the same time of great inhomogeneity within the space occupied by the object of treatment, can not be realized in this manner.

The other advantages enumerated above, such 35 as the possibility of group treatment, and other advantages, cannot be obtained either by the employment or development of this method.

Examples of apparatus for the carrying out 40 of the invention are shown in the accompanying drawings, in which:

Fig. 1 shows, in perspective view, a therapeutic set according to the invention, in the form of a small scale wave-sender mounted on a stand.

Fig. 2 is a diagram of connections for a push-pull arrangement of the wave-sender.

Fig. 3 shows a diagram of connections for an oscillator with a radiating element.

Figs. 4 and 5 show diagrams of connections 50 for two types of apparatus operated from an outside transmitting station.

Fig. 6 illustrates various kinds of treatment with independent conductors, in views I-VI.

Fig. 7 shows an example of a small capacity 55 wave-sender having a battery as a source of current.

The casing 1 of the therapeutic apparatus consists of non-conducting material, such as wood, ebonite, synthetic resin, or the like, and is attached, in the example shown in Fig. 1, to an arm 2 which is universally adjustable about a ball joint 3, and which is mounted on a stand 4. The arm 2 is vertically adjustable by means of the sleeve 5, on the column of the stand, and can be fixed in any desired position by means of the set-screw 6, so that the apparatus can be readily brought up to the part to be treated. The current supply to the sender 7 is by means of a flexible cable 8 having a plug 10 for connection to a receptacle 11 of an electric lighting main. The casing 1 is provided with a handle 12 to facilitate manipulation and transportation. The casing is preferably totally enclosed and merely provided with a few small ventilation holes for the cooling of the transmitting valves.

A measuring instrument 8 enables the oscillation to be checked. This instrument can also be replaced by a small lamp or neon tube. The sender radiates high frequency energy through the walls of the casing.

Fig. 2 shows a diagram of connections by way of example. Two indirectly heated transmission valves 13 and 13' are connected for short waves in a push-pull arrangement with crossed or non-crossed coils 14 and 15, current of the required 10 voltage being derived at 17 from the main.

In the diagram of connections shown in Fig. 3 the valve 13 constitutes with the oscillating circuit elements 19, 20 an oscillator to which there is connected by one pole a radiating element 18. This radiating element 18 consists preferably of a metal plate, wire fabric, or the like, and is housed within the totally enclosed casing; this plate can be shaped, for example, according to the shape of the bottom or of the 20 top of the casing. The sender used can also be constructed, in a known manner, as a quartz-controlled valve sender.

The new electro-therapeutic apparatus has the 25 advantage that no injury to health can be caused by mistakes in use, so that the set, which can be put in operation, for example, like a hot pad, by plugging into any current main, can be safely operated by any novice. Since the set is 30 completely insulated, has no outside treatment electrodes, and generates but very low outputs, the possibility of inflicting burns is effectually precluded. Disturbances of wireless reception are reduced to a minimum by the dimensioning of all the parts for minimum output.

A further widening of the range of applicability is achieved by the possibility of running the set from batteries or accumulators which also supply current of the requisite voltage for the anode, with the aid of a vibrating or rotary voltage transformer. Fig. 7 shows a diagram of connections in which, by way of example, two dry batteries of 4 volts each are used for the current supply, and an inductor 37 with a make-and-break 38 serves as a current converter. The 40 batteries are denoted by 36, and the two transmission valves by 40, 40'. 41 is a resistance, 42 a choke coil, and 43, 44 two condensers. A switch 45 serves for the closing and interruption of the battery current circuit. It will be 45 clear without further explanation that a battery or accumulator can also be employed in conjunction with other known arrangements of connections, as a current source for a small capacity 50 sender of the type described. In place of the inductor with make-and-break contacts there can be employed a rotary converter for supplying current of the voltage required for the anodes.

Figs. 4 and 5 show diagrammatically arrangements by which it is possible to make use, for therapeutic purposes, of the waves transmitted by the various existing broadcasting stations, it being advisable in this connection, with a view to avoiding disturbances, to employ the wave of the local sender. The current voltages received from the broadcasting transmitting station are used for the controlling of an independent wave-sender which generates the high frequency alternating field used for the treatment.

In the diagram of connections shown in Fig. 4, the high frequency amplifying valves, which are coupled together in any desired manner, are denoted by 21 and 22. 23 and 24 denote the rectifier and the low frequency amplifier, re-

spectively, while 25 indicates the coupling between the terminal high frequency amplifier and the rectifier, which coupling takes the form in Fig. 4 of an oscillating circuit coupled by means 5 of a transformer. To the terminals of the oscillating circuit there can then be connected, by means of a suitable line 26, a further amplifier 27 to which latter there is connected the treating circuit 28 arranged to suit the particular 10 needs of the moment.

According to a further variation of the invention, the conductors 26 can be connected to the terminals provided on most wireless receiving sets for gramophone record reproduction. These 15 terminals are connected, in all receiving sets, between the grid and the cathode of the rectifier valve, and thus carry high frequency voltage which can be employed for the operation of the therapeutic amplifier in accordance with the 20 present invention.

Fig. 5 shows diagrammatically how the leads 26, with the amplifier 27 and treating current circuit 28, can be connected up to the terminals 25 29 for gramophone record reproduction on the receiver set 20.

In accordance with the invention the energy transmitted from a powerful sender can be utilized for treatment, by altering at will the distribution of field strength, by means of metallic 30 conductors.

In the arrangement shown in Fig. 6, 31 denotes the wave-sender, 32 and 34 the conductors, 33 the patient, 35 a frequency-determining tuning element connected to the conductor 32. The 35 shape of the conductors can be varied to any extent. The conductors denoted by 32 are in the form of plates which can also be adapted to conform to the shape of certain parts of the body. The conductors denoted by 34 are designed to carry the weight of the patient, and may form part of a chair, bed, or the like. For the treatment of certain parts of the body the conductors are suitably shaped for application to or for the supporting of these parts.

45 The conductors may consist of sheet metal, or metal wire fabric of any kind, or equally, may consist of vessels filled with conductive liquid. In accordance with a particular form of construction of the invention the surface of the conductors is profiled, for example provided with pointed excrescences.

As will be clear from the drawings, a number of patients can be treated simultaneously and at varying distances from a single center 1.

55 In the mode of treatment illustrated at I in Fig. 6 there are provided two conductors 32 and one conductor 34, the latter being in the form of a chair. The patient 33 sits upon the chair conductor 34 and has his head between the conductors 32. In this case the parts of the patient located between the conductors are traversed without the necessity, as with the arrangements for treatment in an electro-magnetic field hitherto known, for the direct supply of energy to the 60 patient or to electrodes included in the treating circuit, from the wave-sending apparatus. With this arrangement one of the conductors 32 and the conductor 34 are earthed.

In Arrangement II the conductor 34, which

takes the form of a ground plate, and carries the weight of the patient, is earthed, while the other plate-shaped conductor 32 is not earthed. The functioning of this arrangement is the same as that of I.

5 Arrangement III shows a further example in which the patient stands on an earthed conductor 34 in the form of a ground plate. The second conductor 32 is connected to a frequency-determining tuning element 35, for instance a turning 10 condenser or a self-induction coil.

In Example IV there is provided but a single conductor 32, the permeation of the patient 33 taking place by capacitive action in a region determined by the position of the conductor 32. As 15 shown in this example, the conductor can also be shaped to conform to any part of the body treated.

In Example V the conductor 32 is likewise connected to a tuning element 35, and the permeation or traversing of the patient by the waves is again effected by capacitive action. The conductor 32 can in this case also be earthed.

In Example VI there is provided only one non-earthed ground plate 34.

25 What I claim is:

1. A short-wave electro-therapeutic apparatus comprising a closed casing, a low power oscillator wholly enclosed in said casing and including a primary oscillatory circuit forming a treatment electrode, said casing consisting, at least at the point adjacent said oscillatory circuit, of a material of high electromagnetic wave permeability, said casing with the oscillator therein being easily transportable and applicable to the part of the 30 patients body to be treated.

2. An apparatus as claimed in claim 1, characterized in that the oscillator is extraneously controlled and connected for operation at the proper point with a broadcast receiver in operation, for instance at the terminals of an oscillation 40 circuit coupled between the high frequency amplifier and the rectifier of said receiver.

3. Apparatus as claimed in claim 1 in which the said wave-sender is of the radio valve type, 45 and further comprising a totally enclosed casing of insulating material containing the said wave-sender, radiating elements located within the said casing, batteries for the direct supply of heating current to the valves of the said wave-sender, and 50 a transforming device interposed between the said batteries and the anodes of the said valves.

4. Apparatus according to claim 1 characterized by the fact that the set is mounted so as to be universally adjustable, on a stand.

5. A short wave electro-therapeutic apparatus comprising a relatively thin flat casing capable of convenient portability and applicable to the part of the patient's body to be treated, a low power oscillator wholly enclosed in said casing 60 and including a primary oscillatory circuit forming a treatment electrode, said casing consisting, at least at the point adjacent said oscillatory circuit, of a material of high electromagnetic wave permeability, a supporting stand, and means adjustably connecting said casing with said stand, whereby the height and angular position of the 65 casing may be varied.

EUGEN WEISSENBERG.
